(57) **CLAIM**

I claim the ornamental design for a nipper, as shown and described.

DESCRIPTION

FIG. 1 is a perspective view of a nipper showing my new design;

FIG. 2 is a front elevation view thereof;

FIG. 3 is a rear elevation view thereof;

FIG. 4 is a left-side elevation view thereof, wherein the right-side view is a mirror image; and,

FIG. 5 is a top plan view thereof, wherein the bottom plan view is a mirror image.

The broken lines shown represent unclaimed subject matter and form no part of the claimed design.
